CAR DOOR

Frank Ditchfield, Cleveland, Ohio, assignor to
The Youngstown Steel Door Company, Cleve-
land, Ohio, a corporation of Ohio

Application June 15, 1945, Serial No. 599,683

3 Claims. (Cl. 189—46)

1

This invention relates to car doors and is directed more particularly to metallic car doors embodying corrugated panels.

It is an object of this invention to provide car doors of requisite strength capable of utilizing corrugated panels formed of lightweight ferrous or non-ferrous metals.

A further object is to provide car doors of normal depth, each door utilizing two corrugated panel sheets formed of lightweight metal having corrugations substantially one-half the depth of the door.

A further object is to provide car doors utilizing two corrugated panel sheets formed of lightweight metal having corrugations substantially one-half the depth of the doors, each of the panel sheets being inadequate to serve as a door panel and the two panels being secured together to constitute an adequate door panel for doors of normal depth.

A further object is to provide corrugated doors utilizing lightweight metallic panel sheets capable of being corrugated without splitting.

A further object is to provide corrugated metallic car doors so designed and constructed as to introduce important economies in construction, labor, and cost by the elimination of parts, operations to be performed, machinery and equipment required, die set-ups, and the like.

A further object is to provide car doors of the character set forth which shall accommodate door supporting fixtures in such manner that the overall width of the cars between fixtures shall lie within the prescribed A. A. R. tunnel clearance diagram.

Other objects of the invention will become clear as the description thereof proceeds.

In the drawings forming part of this specification,

Fig. 1 is an elevation illustrating a door embodying the instant invention.

Fig. 2 is a vertical section taken on line 2—2 of Fig. 1.

Fig. 3 is a horizontal section taken on line 3—3 of Fig. 1.

Referring to the drawings, the instant invention is embodied in a door designated generally by the reference numeral 10. The door 10 embodies two panel sheets 11 and 12, each of which is formed of lightweight metal, as for example, any of the well known narrow gauge regular or alloy steels, or aluminum alloys. The outer panel sheet 11 is preferably formed of three panel sections 13, 14 and 15. The inner panel sheet 12 is also preferably formed of three panel sections 16, 17 and 18. Each section of the outer panel

2

sheet is corrugated horizontally to provide a plurality of alternating crests 19 and troughs 20. The upper horizontal panel section 13 terminates in a partial crest 21, and the lower horizontal margin of the outer panel section 15 terminates in a partial crest 22 of greater length for a reason which will hereinafter appear.

Each section of the inner panel sheet 12 is similarly corrugated to provide a plurality of alternating crests 23 and troughs 24. The upper horizontal margin of the inner panel section 16 terminates in a partial trough 25 and the lower horizontal margin of the inner panel section 18 terminates in a partial trough 26 of the same length as the partial crest 22.

The lower horizontal margin of panel section 13, the upper and lower horizontal margins of panel section 14 and the upper horizontal margin of panel section 15 all terminate in partial troughs 27, 28, 29 and 30, respectively, by the reference numerals 27, 28, 29 and 30. The lower horizontal margin of panel section 16, the upper and lower horizontal margins of panel section 17, and the upper horizontal margin of panel section 18 terminate in partial crests, the crests at the lower and upper horizontal margins of panel sections 16 and 17 being shown and designated by the reference numerals 31 and 32.

Adjacent to their forward vertical edges the troughs of the outer panel sections 13, 14 and 15 are inclined forwardly and outwardly as indicated at 33, 34 and 35, the said inclined portions terminating in flanges 36, 37 and 38 which lie in the plane of the crests 19. Adjacent to their rear vertical edges the troughs of the outer panel sections are inclined rearwardly and outwardly as indicated at 39, 40 and 41 and terminate in flanges 42, 43 and 44 which also lie in the plane of the crests 19.

Similarly, the crests 23 of the inner panel sections 16, 17 and 18 are inclined forwardly and inwardly adjacent to their forward vertical edges as indicated at 45, 46 and 47, and rearwardly and inwardly adjacent to their rear vertical edges, the said latter inclination of panel section 16 being shown at 48. The inclined portions 45, 46 and 47 terminate in flanges 49, 50 and 51 lying in the plane of the troughs 20. The inclined portions of the inner panel sections 16, 17 and 18, as exemplified at 48, terminate in flanges which also lie in the plane of the troughs 20. This flange of panel section 16 is shown at 52.

The door 10 also embodies metallic marginal reinforcing members to which the panel sheets are secured in the manufacture of the door. The

reinforcing members comprise an upper horizontal member 53 formed with a depending flange 54, an inwardly extending web 55, an upstanding flange 56, and an inwardly directed flange 57. Angle members 58 and 59 constitute the lower horizontal reinforcing members and are arranged with the legs 60 and 61 vertical and the legs 62 and 63 horizontal and extending toward each other. If desired, the horizontal legs 62 and 63 may be welded together.

The front vertical reinforcing member 64 is substantially Z-shaped in section and includes a rearwardly directed flange 65, an inwardly extending web 66, and a forwardly extending flange 67 which is bent outwardly to form a flange 68 adapted to abut a front door stop 69 secured to a door post 70 and cooperating with member 64 to resist entry of foreign matter when the door is closed. The rear vertical reinforcing member 71 is substantially W-shaped in section and embodies a forwardly extending flange 72, an inwardly extending web 73, a rearwardly extending flange 74, which carries a sealing strip 75 cooperative with a weather strip 76 secured to a door post 77 by means of an angle member 78 to resist entry of foreign matter when the door is closed, and an inwardly directed buffer flange 79. Each of the marginal reinforcing members is preferably formed of a material of heavier gauge than the material from which the panel sheets are formed.

The relationship of the panel sheets in the formation of a door panel and their relationship to the marginal reinforcing members are clearly shown in Figs. 2 and 3 of the drawings. The panel sections of the outer and inner panel sheets 11 and 12 are related in such a manner that the crests 23 of the inner panel sections engage the troughs 20 of the outer panel sections and the troughs 24 of the inner panel sections are opposed to the crests 19 of the outer panel sections. The arrangement is such that a series of horizontally extending box sections is provided in the door panel from top to bottom of the door. At the joint between upper panel sections 13 and 16 and intermediate panel sections 14 and 17, which occurs between box sections, the partial trough 28 of section 14 and partial crest 32 of section 17 are overlapped and disposed between and riveted or otherwise secured to partial trough 27 of section 13 and partial crest 31 of section 16 as more clearly shown in Fig. 2 of the drawings. The intermediate panel sections 14 and 17 and the bottom panel sections 15 and 18 are similarly jointed between two box sections.

The box section construction is secured as well at the marginal portions of the door and this without the use of additional backing plates. A box section is obtained along the upper horizontal margin of the door between panel sections 13 and 16 and reinforcing member 53. The partial crest 21 of the outer panel section 13 is secured preferably to the inner face of the depending flange 54 as by means of rivets or the like. Similarly, the partial trough 25 of the inner panel section 16 is secured to the inner face of the upstanding flange 56 of the reinforcing member 28.

At the lower margin of the door the partial crest 22 of the outer panel section 15 is secured preferably to the outer face of the vertical leg 60 of angle member 58 and partial trough 26 of the inner panel section 18 is secured preferably to the inner face of the upstanding leg 61 of the angle 59.

At the front vertical margin of the door a box

section is obtained by the securement of flanges 36, 37 and 38 of the outer panel sections 13, 14 and 15 to the rearwardly extending flange 65 of the reinforcing member 64 and flanges 49, 50 and 51 of the inner panel sections 16, 17 and 18 to the forwardly extending flange 67. At the rear vertical margin of the door the flanges 42, 43 and 44 of the outer panel sections are secured to the forwardly extending flange 72 of reinforcing member 71 and the flanges of the inner panel sections, such as flange 52 of section 16, are secured to flange 74 of reinforcing member 71 to form a box section.

It will be apparent from the foregoing description that the marginal flanges of the outer panel sheet 11 lie substantially in the outer plane of the door and the marginal flanges of the inner panel sheet 12 lie substantially in the inner plane of the door. Similarly, the crests 19 in the outer panel sheet 11 are disposed substantially in the outer plane of the door and the troughs 24 of the inner panel sheet 12 lie substantially in the inner plane of the door. The opposed crests 23 of the inner panel sheet 12 and troughs 20 of the outer panel sheet 11 lie substantially in the median plane of the door. By virtue of this construction the corrugations formed in the outer and inner panel sheets are only one-half of the depth of the door so that it becomes possible to utilize thin and lightweight corrugated metallic panels in railway house car doors without danger of splitting or creasing the panels in the formation of the corrugations.

As indicated in the drawings, the outer and inner panel sheets are riveted or otherwise secured together between the box sections formed by the panel sheets, thereby causing the separate panel sheets to act as a unitary door panel to resist stresses imposed thereon. In this way, despite the fact that lighter and thin 16, 18 and 20 gauge metallic panel sheets, each of which alone is inadequate to provide a satisfactory door panel, may be utilized in place of the standard corrugated 13 gauge sheets, the arrangement and securement of the panel sheets provide a corrugated door panel of requisite strength and depth.

As more clearly illustrated in Fig. 3 of the drawings, the inwardly inclined portions of the inner panel adjacent to the vertical margins of the door make it impossible for lading to lodge against the inner face of the door so as to impede its opening movement.

The construction at the lower horizontal margin of the door, as more clearly illustrated in Fig. 2 of the drawings, provides ample room for the reception of a door supporting lift fixture designated generally by the reference numeral 80. In this manner, the projection of the lift fixture is restricted so that the overall width of the car measured between lift fixtures on opposite sides thereof lies within the prescribed A. A. R. tunnel clearance diagram.

The horizontal legs 62 and 63 of the bottom reinforcing angle members 58 and 59 constitute a base upon which the door is frictionally supported when in lowered position upon a door track 81 secured to the car underframe 82 by means of a plurality of brackets, one of which is illustrated at 83. The door is retained upon the track by means of a plurality of hook-shaped members 84 which embrace the depending leg 85 of the door track.

At the top the upstanding flange 56 of the reinforcing member 53 is received between the depending flange 86 of a substantially Z-shaped re-

taining bar 87 and the upstanding leg 88 of a trough-shaped header 89 fastened to the depending flange 90 of the customary side plate. The inwardly extending flange 57 of the reinforcing member 53 lies above the header 89 and cooperates therewith to prevent the entrance of foreign matter into the car over the top of the door.

As a result of the instant invention each pair of inner and outer panel sections is formed on the same die set-up, variations in the height or width of each pair of sections being concentrated in the marginal flanges. The door of the instant invention, moreover, eliminates the customary marginal bridging plates heretofore utilized. Thus the number of die set-ups heretofore required are substantially reduced. A reduction in the number of parts required is, therefore, obtained as well as a reduction in the number of operations to be performed and in the machinery and equipment required therefor. The resulting reduction in cost is evident. The normal depth of door of about 1½" is maintained.

The box sections created throughout the door panel provide a strength substantially two and one-half times as great as that of open corrugations having a depth equal to the depth of the box sections. As shown the crests and troughs are identical in cross section thereby simplifying and reducing the cost of the die.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. A car door comprising a substantially rectangular metallic panel and reinforcing members therefor, said panel consisting of inner and outer sheets formed of lightweight metal and having horizontal corrugations, the troughs of the corrugations of the inner panel sheet and the crests of the corrugations of the outer panel sheet being opposed and lying, respectively, substantially in the inner and outer planes of the door, the crests of the corrugations of the inner panel sheet and the troughs of the corrugations of the outer panel sheet being opposed and lying intermediate the inner and outer planes of the door, means rigidly securing certain of the crests of said inner panel sheet and troughs of said outer panel sheet together so that said panel sheets act as a unitary door panel to resist stresses, said reinforcing members being secured to the margins of said door panel, the troughs of the corrugations of said panel sheets merging gradually into the vertical margins of said panel sheets, the depth of said door being substantially the same as the depth of metallic car doors in general use.

2. A car door comprising a substantially rectangular metallic panel and reinforcing members therefor, said panel consisting of inner and outer sheets formed of lightweight metal and having horizontal corrugations, the troughs of the corrugations of the inner panel sheet and the crests

of the corrugations of the outer panel sheet being opposed and lying, respectively, substantially in the inner and outer planes of the door, the crests of the corrugations of the inner panel sheet and the troughs of the corrugations of the outer panel sheet being opposed and lying substantially in the median plane of the door, means rigidly securing certain of the crests of said inner panel sheet and troughs of said outer panel sheet together so that said panel sheets act as a unitary door panel to resist stresses, said reinforcing members being secured to the margins of said panel sheets, the margins of the inner panel sheet lying substantially in the inner plane of said door and the margins of the outer panel sheet lying substantially in the outer plane of said door, the troughs of the corrugations of said panel sheets merging gradually into the vertical margins of said panel sheets, the depth of said door being substantially the same as the depth of metallic car doors in general use.

3. A car door comprising a substantially rectangular metallic panel and reinforcing members therefor, said panel consisting of inner and outer sheets formed of lightweight metal and having horizontal corrugations, the troughs of the corrugations of the inner panel sheet and the crests of the corrugations of the outer panel sheet being opposed and lying, respectively, substantially in the inner and outer planes of the door, the crests of the corrugations of the inner panel sheet and the troughs of the corrugations of the outer panel sheet being opposed and lying substantially in the median plane of the door, means rigidly securing certain of the crests of said inner panel sheet and troughs of said outer panel sheet together so that said panel sheets act as a unitary door panel to resist stresses, said reinforcing members being secured to the margins of said panel sheets, the margins of the inner panel sheet lying substantially in the inner plane of said door and the margins of the outer panel sheet lying substantially in the outer plane of said door, the troughs of the corrugations of said panel sheets merging gradually into the vertical margins of said panel sheets, the depth of said door being substantially the same as the depth of metallic car doors in general use, the lower reinforcing members being angular in section and disposed between and secured to the lower margins of said panel sheets, each of said latter reinforcing members having a vertically disposed securing leg and a horizontally disposed door supporting leg.

FRANK DITCHFIELD.
